UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, AND BOSTON, MASSACHUSETTS, A CORPORATION OF NEW JERSEY.

PULLING-OVER MACHINE.

1,077,938.

Specification of Letters Patent.

Patented Nov. 4, 1913.

Application filed March 28, 1903, Serial No. 149,967. Renewed January 19, 1912. Serial No. 672,236.

To all whom it may concern:

Be it known that I, RONALD F. McFEELY, a citizen of the United States, residing at Beverly, in the county of Essex and Commonwealth of Massachusetts, have invented 5 certain Improvements in Pulling-OVER Machines, of which the following description, in connection with the accompanying drawings, is a specification, like reference characters on the drawings indicating like parts in the several figures.

10 This invention relates to pulling-over machines, which are used for preparing shoes for lasting by performing the operation known as "pulling-over" the shoes.

15 Important features of this invention are found in the mechanism for actuating the shoe resting means, which may comprise either the shoe bottom or sole rest or the shoe end or heel rest, or both of said rests.

20 One feature is found in the combination with pulling-over means, a rest for the last, as for example for the heel end of the last, and actuating mechanism for said rest, of 25 a manually operated lever normally connected with said actuating mechanism and means for disconnecting said lever from said mechanism. Said actuating mechanism may advantageously include a cam and a 30 shaft operatively connected therewith and a second shaft with means for adjustably connecting the shafts whereby the position of the rest relatively to its driving cam can be adjusted.

35 Another feature of this invention consists in the combination with a sole rest, a heel rest, and manually operated means normally connected with the said rests for actuating them, with or without provision for disconnecting said manual actuating means from 40 one of said rests so that the other rest may be moved alone, or with or without provision for permitting one of said rests to be moved by said manual actuating means farther than the other rest is moved.

45 The machine may also have means for locking one rest after it has been moved and permitting further movement of the other rest by said manual means. Preferably there is provision for returning said 50 rests, which may have been moved through the same or different distances, always to the same initial position. In the illustrated

construction, certain characteristics of which are new by this invention, a lever is normally connected with both rests for actuating them manually, the connection being made through a novel arrangement of pawls and a pawl disengaging device that is arranged to act on the pawls successively. 55 Preferably there is means arranged to become operative after the disengaging device has disengaged one of the pawls to warn the workman that further movement will disengage another pawl. This result may be 60 obtained for example by a plurality of springs offering a change in resistance when the successive pawls are about to be acted upon by the disengaging device.

65 Another feature of the invention consists 70 in the combination with the rests and said manually operated means, of mechanisms for automatically actuating the rests and holding them in actuated position independently of said manual operating means, with 75 or without provision for disconnecting one of the rests from the automatic means to permit of manual operation of the other rest in either direction.

80 These and other features of the invention including certain details of construction and combinations of parts will appear more fully 85 from the description in connection with the drawings and will be pointed out in the claims.

85 Many novel features which are of my invention and are shown and described in this application are claimed in United States Letters Patent No. 1,029,387, granted June 11, 1912, on an application filed concurrently 90 with this application.

95 Figure 1 is a front elevation of a pulling-over machine embodying my invention in one of the best forms now known to me. Fig. 2 is a view of the left side of the machine. Fig. 3 is a view showing the lower portion of the machine in central vertical section, other portions being shown in side elevation. Fig. 4 is a view of the heel-rest and of the sole-rest, together with the mechanism for actuating said rests to move the last forward with relation to the pulled upper and to move the sole over the bottom of the last to bring its front end flush with the toe of the last. The parts are shown in 100 the position which they occupy after the

grippers have gripped the upper and before they have begun to pull the upper. Fig. 5 is a view showing the position of the parts illustrated in Fig. 4, after the automatic 5 operation of the machine by which the grippers have pulled the upper, the last has been depressed and moved forward into the pulled upper and the sole has been moved toward the toe of the last. Fig. 6 shows 10 the position of the parts after the sole-rest has been manually operated to move the sole farther forward to bring its edge flush with the toe of the last. Fig. 7 is a sectional view on lines 7—7 of Fig. 4. Fig. 8 is a 15 rear end elevation of the sole-rest and heel-rest operating mechanism shown in Fig. 4. Fig. 9 is a plan view of a portion of the mechanism shown in Fig. 5 for moving the sole-rest and the heel-rest. Fig. 10 is a 20 view looking to the right from the dotted line 10—10, Fig. 8. Fig. 11 is an enlarged view of certain parts shown in Fig. 4 in another position. Fig. 12 is a view similar 25 to Fig. 11, showing the parts in still another position. Figs. 13 and 14 are views of a device for adjusting the heel-rest operating shaft. Figs. 15 and 16 are views of the heel-rest and sole-rest operating 30 pawls, and the adjustable devices for determining the relation of their times of engagement with their ratchet wheels. Fig. 17 is a detail side view of the heel-rest. Fig. 18 is a detail front view of the heel-rest. Fig. 19 is a sectional view on line 19—19, 35 Fig. 17, showing the means for preventing lateral movement of the heel-rest after the last has been clamped. Figs. 20 and 21 are plan and side views, respectively, of the means for sustaining and actuating the arms 40 which carry the mechanisms for supporting the last while fastenings are being inserted and for wiping and pressing the pulled-over portion of upper into place to receive 45 said fastenings.

The head B of the machine is supported on a post 12* which is vertically adjustable in the column A.

D indicates the main shaft, see Fig. 3, mounted in bearings in the head and driven 50 by a pulley 986* connected thereto by a series of speed-reducing gears X¹⁹, X²⁰, X²¹, X²². The pulley is driven by a belt from a suitable driving shaft and is acted upon by a brake 982* supported on a rod 984*. Cams X³⁰ and 188* are carried by 55 the driving shaft and have connection with gripper operating levers 154*, 154*, and e'.

804* indicates a groove cam having connection, by means not herein shown, with 60 a plate 814* which is pivotally supported on a shaft 812* and is oscillated on said shaft by the rotation of the cam 804*. The plate 814* is connected with the several tack driver bars 680*, 682*, and 694* to lift 65 said bars. The driver bars are depressed

to insert the tacks by a spring 708* acting through a shaft 706* and an arm 718*, the free end of which rests on a plate 720* which bears on the upper ends of the driver bars. A slide 818* is mounted for longitudinal movement in the plate 814*, being actuated by a pinion 822* formed on the shaft 812*. The slide has connection (not shown) with guides 672*, 674*, and 676* through which the driver bars move, and 75 acts to swing said driver bars laterally to move their lower ends toward and from the work. Tack carriers 640*, 600*, and 656* are carried by the guides and are moved laterally with the drivers toward and from 80 the work. The shaft D carries an eccentric 410* surrounded by a strap which is connected through a rod 408* to a lever 404*, which has a rack and pinion connection with the shaft 398 of the tack hopper 400* 85 for oscillating said hopper to cause the tacks to be fed therefrom. These mechanisms are preferably the same as the corresponding mechanisms shown and described in Letters Patent of the United States No. 90 663,777 granted Dec. 11, 1900, and reference may be had thereto for a detailed illustration and description of these parts of the machine.

The shoe is prepared for the machine by 95 assembling the upper, lining, counter and inner-sole loosely upon the last and is presented to the machine with the inner-sole against a sole-rest as shown in Fig. 4 of the drawings, and the edge portion of the 100 upper is inserted between the open jaws of the toe grippers and the side grippers. When the machine is started the grippers grasp the upper and pull it upwardly about the last while the heel-rest is moved into 105 engagement with the heel of the last, and thereafter the shoe is held by the heel-rest, sole-rest, and grippers.

The shaft D is provided with a groove cam 6—see Figs. 3, 4, 5, 8, and 21—in which is 110 received a stud 8 on a block 10. The block 10 has a channel or groove in its under side in which is received the upper portion of a block 12 and also a spring 14 which is interposed between shoulders 16 and 18 on the end portions of the blocks 10 and 12 respectively. This arrangement is such that movement of the block 10 by the cam 6 is communicated yieldingly to the block 12 through the spring 14. The block 10 is 115 positively moved by the cam 6 and is connected through mechanism later to be described with the sole-rest 2 for moving the sole-rest forwardly.

Motion is communicated from the block 12 to the heel-rest 4 through the following mechanism: The block 12 is connected by means of a rack and pinion 20, 22 with a vertical shaft 24. Motion is communicated from the shaft 24 through beveled gears 26, 125 130

28 to a horizontal shaft 30 which extends transversely of the machine. The shaft 30 is connected to a sleeve shaft 32 by means of a clutch, located at the end of the shaft 30 opposite to that on which the beveled gear 28 is secured. The clutch comprises, see Figs. 13 and 14, a collar 34 rigidly attached to the shaft 30, and a collar 36 freely movable on the end portion of the said shaft 30 and provided with fingers 38 which are adapted to enter alined recesses 40 formed in the collar 34 and in the end of the loose collar shaft 32. The sleeve 36 is held normally, by a spring 42, with the fingers 38 in the recesses 40 of the fixed collar 34 and the shaft 32, thereby locking the shafts 30 and 32 together, as shown in Fig. 13 but may be moved against the tension of said spring 42 to withdraw the fingers from the notches and thereby uncouple the shafts 30 and 32, as shown in Fig. 14.

The sleeve shaft 32 is provided with pinions 44, 44—see Figs. 4, 8, and 9—for engagement with rack-teeth formed on bars 48, 48, which are mounted for sliding movement through the post 12^x, as shown in Figs. 2 and 3. The bars 48, 48 carry the heel-rest 4 on their front ends.

The heel-rest is connected to the bars 48, 48 by means of collars 50 loosely mounted on the reduced ends of the bars and confined thereon by nuts 52, as shown in Figs. 4 and 5. Hangers or supports 54 for the heel-rest are connected to the collars 50 by transverse pivots 56. The hangers 54 extend downwardly and backwardly and at their lower ends are provided with trunnions 64 on which is mounted the heel-rest. These connections between the heel-rest and the two bars 48, 48 permit the heel-rest to be swung laterally toward either side of the machine to adapt it to receive heels of lasts which differ in shape and to accommodate it to the lateral position which different shapes of shoes are required to assume in the machine.

A yoke 66 is connected to the bars 48, 48 in the rear of the heel-rest and is provided at 68 with a roughened surface, see Figs. 17 and 19. A plate 70 is supported by the heel-rest hangers 54 in position to engage the roughened surface 68 of the yoke when the heel-rest is pressed backwardly. The movement of the heel-rest hangers on the pivots 56 is limited by engagement of shoulders 58 and 60 with the under sides of the collars 50. The shoulders 60, which are located in the rear end of the pivots 56, contain springs 62 which bear against the collars 50 and normally hold the hangers tilted forward as far as the shoulders 58 permit, as shown in Fig. 17. In this forward position of the heel-rest the plate 70 is out of contact with the yoke, so that the heel-rest is free to swing laterally, but

when the rest engages the shoe it is moved backwardly far enough to cause the plate 70 and the surface 68 of the yoke to come into frictional contact, and when these parts are in contact the heel-rest is locked against lateral movement. The springs 62 are strong enough to hold the heel-rest away from the yoke where it is free to move laterally, until the rest, in its forward movement imparted by the spring 14 and the block 12, meets the shoe. As the rest comes into contact with the shoe it is moved laterally by its inclined faces 41, 41 as they meet the shoe and automatically adjusts itself laterally according to the shape of the last and the position which the shoe has assumed in the machine. When the rest is so pressed against the shoe it will yield backwardly against the tension of springs 62 until it meets the roughened surface 68 of the yoke and thereby becomes locked against any subsequent lateral movement during the operation of the machine.

The heel-rest actuating mechanism above described, including the block 10, acts to move the heel-rest forwardly automatically until it comes into contact with the heel of the shoe, after which the spring 14 yields during the further movement of the heel-rest is sufficient to accommodate considerable variation in the length of lasts. For accommodating widely different lengths of lasts the heel-rest may be adjusted backwardly and forwardly by uncoupling the shafts 30 and 32 in the manner above described. When these shafts are uncoupled the heel-rest may be shifted freely either backwardly or forwardly into the desired position. In this movement the sleeve shaft 32 turns idly on the shaft 30, and when the proper adjustment has been found the shafts 30 and 32 may be again coupled, and thereafter the heel-rest will be operated in its new position by its actuating mechanism.

If it is desired to discontinue the automatic actuation of the heel-rest the shafts 30 and 32 may be disconnected by drawing the loose collar 36 to the left in the several figures, as above described, and then turning it until the fingers 38 are out of alinement with the recesses 40 and in position to rest against the left-hand side of the collar 34 on the shaft 30. This uncouples the collar and its shaft 30 from the sleeve shaft 32 and permits the sleeve shaft, and therefore the heel-rest, to remain unmoved while the shaft 30 continues to be automatically oscillated.

The yieldingly effected, automatic advance of the heel-rest takes place during the first part of the movement of the grippers for drawing the upper taut around the last and is preferably just sufficient to bring the heel-rest into operative position against the

heel of the shoe, but is not designed for moving the shoe forwardly. The spring 14 could, of course, be made strong enough to cause the shoe to be pushed forwardly by this mechanism if desired.

5 It is sometimes desired in pulling-over shoes to give the upper a backward and upward pull over the ball after it has been pulled straight upwardly. This is known as 10 "back-lasting" and is accomplished when 15 shoes are pulled over by hand, by turning the pincers and giving the upper a pull angularly across the last. In the machine herein shown the same result is obtained 20 by giving the last a forward movement into the suspended upper during the last part of the rise of the grippers. This causes the side grippers to pull the upper backwardly and upwardly and so draw the upper firmly 25 over the ball of the last. I have in this embodiment of my invention moved the shoe forwardly by means of the heel-rest and for this purpose have provided for the heel-rest actuating mechanism now to be described.

25 The block 10, which is actuated directly and positively by the cam groove 6, as before described, is provided on its lower face with a lug 80 for engaging one arm 82 of a bell-crank lever 84 which is mounted on a 30 fixed stud 86. The other arm 88 of the bell-crank lever rests upon a plunger 90, which carries at its lower end a pawl 92 comprising part of the heel-rest actuating mechanism and a pawl 94 comprising part of a 35 mechanism hereinafter referred to. The pawls 92 and 94 are adapted to engage ratchet wheels 96 and 98. The plunger is depressed by the bell-crank lever against the tension of a returning spring 100—see 40 Fig. 8—when the block 10 is moved to the left in Fig. 4. The pawls 92 and 94 are acted upon by springs 102 to force them against the ratchet wheels 96 and 98. Controlling devices 104 and 154 for disengaging 45 the pawls from the ratchet wheels are adjustably mounted on a fixed portion of the frame—see Figs. 4, 15, and 16—in position to contact with the upper ends of the pawls and disengage them from the ratchet wheels 50 as the plunger 90 rises. These controlling devices hold the pawls away from the ratchets until the pawls pass them in the descent of the plunger. The position to which the controlling devices are adjusted determines 55 the portion of the downward stroke of the plunger during which each pawl is allowed to engage its ratchet, and therefore determines the extent of movement imparted by the plunger to each of the ratchet wheels.

60 The ratchet wheel 96 is formed on a sleeve shaft 150 which carries a pinion 152. The pinion 152 engages the rack-teeth on one of the heel-rest carrying bars 48. The positive movement of the cam-operated sliding block 65 10 is therefore transmitted through the

plunger 90 and said sleeve shaft 150 to the heel-rest carrying bars 48, to force the heel-rest, and therefore the last, forwardly into the suspended upper. This movement preferably takes place during the last part of the rise of the grippers and strains the upper backwardly over the ball of the last.

70 The sole-rest is actuated for moving the inner-sole by mechanism including the pawl 94 and the ratchet wheel 98 above mentioned. The ratchet wheel 98 is formed on a shaft 110 independently movable inside the sleeve shaft 152, said shafts extending transversely of the machine, parallel with the shafts 30 and 32 as shown in Fig. 9. The shaft 110 is provided with a pinion 112 which engages with rack-teeth formed on a bar 114 slidably mounted in the post 12^x of the machine frame, as shown in Figs. 3, 4 and 9. The bar 114 is provided at its rear end with a spring 115 which abuts against the machine frame and which tends to hold the bar in its rearmost position and the bar is pivotally connected by a link 116 to the shank 118 of the sole-rest. The shank of the sole-rest is guided through a sole rest carrier 120 which is mounted on a fixed pivot 122. The shank 118 is provided with a T rib which is received in a suitable guideway in the lower face of the carrier 120, as indicated in Figs. 4 and 5.

90 The sole-rest comprises two laterally and forwardly extended arms 124, 124 for engaging the inner-sole near its edges, and a forwardly extended arm 126 having a foot piece for engaging the inner-sole near the toe end thereof. The arms of the sole-rest are provided with roughened extremities or feet for frictionally engaging the inner-sole to prevent the rest from slipping with relation to the inner-sole and enable the rest to move the inner-sole with relation to the last for a purpose to be described. The arm 126 of the sole-rest is adjustably connected to the shank 118—see Fig. 7—to adapt the sole-rest for properly engaging inner-soles varying in length. This connection comprises a spring-pressed bolt 128 mounted in the shank 118 and adapted to engage any one of a series of notches in the arm 126.

100 The foot-piece 130 of the arm 126 of the sole-rest is adjustably attached to said arm, as shown in Fig. 4. The foot-piece is mounted on a pivot 132 and its rear end is acted upon by a spring 134 which tends to tip the forward end of the foot-piece upwardly.

by the toe-cap, stiffener, and linings in addition to the upper, whereas other shoes have less thickness of upper material to be pulled over by the toe grippers. It is advantageous when there is a considerable thickness of the upper material at the toe to have the shoe held lower than when there is less thickness, and the foot-piece 130 may be adjusted according to the class of shoes being operated upon.

The carrier 120 in which the sole-rest is movable is provided with an arm 138 which is engaged by a cam 140 carried on the front end of the shaft D. The cam tips the carrier 120 on its pivot 122 to force the sole-rest downwardly at a certain period in the operation of the machine. The carrier is tipped in the opposite direction by a spring 142 mounted in a chamber in the rear end 20 of the carrier and bearing against a fixed portion of the machine, as shown in Figs. 3 and 4. This mechanism operates, after the machine is started and while the upper is being pulled taut about the last by the grippers, to sink the last downwardly into the upper.

The pawl controlling devices 104 and 154 may be adjusted to render the pawls 92 and 94 operative or inoperative for moving the sole-rest and the heel-rest. When said pawls are rendered operative the controlling devices determine the portion of the strokes of the pawls which shall be effective for moving the sole-rest and the heel-rest and thereby determine the extent of the forward movement imparted to each of said rests. When it is desired to move the shoe forwardly without changing the position of the inner-sole on the last the controlling devices 40 are adjusted for giving the two pawls the same amount of movement so that the sole-rest and the heel-rest shall be moved forwardly the same distance.

When the inner-sole is loose on the last and it is desired to move it forwardly over the bottom of the last to bring its toe end flush with the toe end of the last and simultaneously to move the last forwardly, the controlling device for the sole-rest actuating 50 pawl will be so adjusted as to render the sole-rest actuating pawl operative for a greater portion of its movement than the heel-rest actuating pawl.

When the inner-sole is loose on the last and it is desired to move the inner-sole forwardly without moving the last the pawl controlling device for the heel-rest actuating pawl will be so adjusted as to render the said pawl inoperative and the pawl controlling device for the sole-rest actuating pawl will be so adjusted as to render the sole-rest actuating pawl effective during the necessary portion of the stroke of said pawl for producing the desired movement of the 65 sole-rest. It is to be understood that if the

inner-sole is loose on the last, that is unattached to it, the sole-rest imparts no movement whatever to the last, but merely moves the inner-sole with relation to the last. If however the inner-sole is fastened to the 70 bottom of the last by tacks or otherwise, as is sometimes done, the sole-rest assists the heel-rest in moving the last forwardly, or the heel-rest actuating pawl might be rendered inoperative and the sole-rest alone be 75 employed for moving the last by means of the inner-sole secured to it.

It is sometimes desirable to move the heel-rest or the sole-rest, or both of them, farther forward after the machine has given 80 to these parts their automatic movement, as above described. At other times it is desirable to discontinue the automatic operations of the sole-rest and the heel-rest for moving the inner-sole and last respectively 85 and manually move said parts as required. For this purpose the machine is caused to come to rest after the upper has been stretched and after these automatic movements have been imparted to the sole-rest 90 and the heel-rest. A hand lever 160 is provided which is attached to the shaft 110, to which shaft is also secured the ratchet wheel 98, as shown in Fig. 9. The hand lever carries a spring-pressed pawl 164 in position 95 to engage the other ratchet wheel 96, as shown in Figs. 8 and 10 so that said hand lever is normally connected to both the shaft 110 of the sole-rest operating mechanism and the shaft 150 of the heel-rest operating 100 mechanism. The pawl 164 has a lateral arm 163 which stands in the path of a device 162 which may be operated to disengage the pawl 164 and also the pawls 92 and 94 from the ratchets 96 and 98. The 105 pawl disengaging device 162 is pivotally connected to the hub of the hand lever at 165—see Figs. 11 and 12—and has a finger-piece 166 standing alongside the lever in convenient position to be operated in connection with the lever. The pawl 94 has a lug 174 which also stands in the path of the disengaging device, so that the two pawls 94 and 164 may be disengaged simultaneously from their respective ratchets. The 110 pawls 94 and 92 are connected by a stud 176 on the inner side of the pawl 94 which enters a slot 177 in the adjacent face of the pawl 92—see Fig. 11. The slot is of sufficient length to allow the stud a limited 115 amount of free movement, after the disengaging device contacts with the lug 174 and begins to move the pawl 94 before the pawl 92 is moved.

The pawl disengaging device 162 is held 120 normally in the position shown in Fig. 4 by a spring-pressed plunger 168, mounted in a socket in the hand lever, and bearing against the finger-piece 166. The socket in the lever also contains a second plunger 170, located 130

in the rear of the plunger 168 and actuated by a spring stronger than the spring which actuates the plunger 168.

When the finger-piece of the disengaging device is depressed to force the pawls away from the ratchets, the plunger 168 will yield readily until its spring has been compressed, as shown in Fig. 11, whereupon the resistance of the second plunger will be encountered and thereafter, if a stronger pressure is applied to the finger-piece than was necessary to depress the first plunger, the second plunger may also be depressed, as shown in Fig. 12. This arrangement is such that the operator may with ease depress the finger-piece to the extent allowed by the first plunger to cause the pawl disengaging device to assume one position, but a distinctly greater pressure will be required to depress the finger-piece to overcome the stronger spring of the second plunger and force the disengaging device into its second position.

When the parts are in their normal position, as shown in Fig. 5, the pawl 164 on the hand lever, is in engagement with the ratchet 96—see Figs. 8 and 10—and when the hand lever is turned toward the dotted line position—Fig. 5—both the ratchets 96 and 98 are turned while the pawls 92 and 94 act as stop pawls to prevent reverse movement of said ratchets. This rotation of the ratchets advances both the heel-rest and the sole-rest together to force the last forwardly into the suspended upper.

Sometimes it is found to be necessary to give the sole-rest a forward or backward movement independent of the heel-rest after the automatic operation of the machine to position the inner-sole accurately on the last, or, if the inner-sole is tacked to the last, to move the last forwardly or backwardly. When this is necessary the pawl disengaging device is depressed into its first position in which it disconnects the pawl 164 from the heel-rest operating ratchet 96 and also holds the stop pawl 94 off from the sole-rest ratchet 98. The hand lever 160 is then free to be turned to rotate the shaft 110 alone in either direction to move the inner sole over the last.

At other times it may be desirable, in order to readjust the last in the upper, to release the heel-rest and let it move backwardly the distance which it has been positively advanced in the back-lasting movement. This can be done by moving the disengaging device into its second position, shown in Fig. 12, whereupon the stud 176 on the pawl 94 will move pawl 92 out of engagement with ratchet 96 to release said ratchet. The heel-rest is then free to be moved backwardly by the tension of the stretched upper.

It will thus be seen that the hand lever

will not only move the sole-rest and the heel-rest forwardly together, but it may also be used to move the sole-rest backwardly and forwardly while the heel-rest is locked against movement, and further, the heel-rest may be released and permitted to move backwardly independently of the sole-rest. It is to be noted that the heel-rest is given an initial forward movement by the cam 6 acting through the spring 14 and that the spring 14 yieldingly holds the heel-rest in the forward position to which it is moved. When the hand lever is operated to advance the heel-rest still farther, the force exerted through said lever by the operator is in addition to the force of the spring and therefore need be but slight in order to effect the movement of the heel-rest and the shoe supported thereby.

In order to permit the heel-rest to return to its normal position if it has been given a manual adjustment in addition to its automatically imparted movement it is necessary to disengage the pawl 164 of the hand lever from the heel-rest operating ratchet 96 after the operation of the machine on one shoe has been completed and before the operation on another shoe is begun. For this purpose a lug 167 is secured to the machine frame, as shown in Figs. 1 and 10, and stands in the path of the pawl 164 to disengage said pawl from its ratchet as the hand lever swings to the rear beyond its central, normal position. The ratchet 96 is then free to rotate independently of the hand lever and of the sole-rest ratchet, to permit the heel-rest to resume normal position under the influence of spring 14.

The shoe is supported for the insertion of the fastening tacks by mechanism comprising arms 20^x and 22^x (Figs. 1, 2, 20, and 21) pivotally supported on the head of the machine at 18^x for horizontal movement together toward and from each other. The arms are in the form of bell-crank levers, and their rear ends are engaged by rack-teeth on bars N²⁴, N²⁵ which are moved by a slide N²⁶. The slide carries a stud N³³ which is acted upon by the cam N³³, whereby said slide is reciprocated to actuate the arms 20^x, 22^x. The movement of the bars N²⁴, N²⁵ by the slide N²⁶ to cause the last-supporting arms to approach each other is yieldingly effected through springs N⁴⁴, N⁴⁰ and an equalizing device N⁷, all substantially as shown and described in detail in Letters Patent of the United States, No. 950,701, granted to me March 1, 1910.

The arms 20^x and 22^x carry on their free ends combined mechanisms for supporting the last and wiping and pressing the pulled upper into position to receive the securing tacks. These mechanisms will preferably be constructed as shown and described in said prior Patent No. 1,029,387.

The toe portion of the upper is wiped and pressed into position for receiving the fastening tacks by the combined wiping and tack-carrying mechanism indicated at 214, in Fig. 2. This mechanism preferably will be the same as that shown and described in Letters Patent No. 950,701, before mentioned and therefore is not shown or described in detail herein.

10. The mechanism for pulling the upper to stretch it around the last comprises grippers 78^x mounted on shanks 68^x. The upper ends of the gripper shanks are pivotally connected to the levers 154^x, 154^x, and e' which are fulcrumed on a pivot shaft 152^x in the machine head and acted upon by cams X³⁰ and 188^x; as heretofore described, whereby said levers are rocked to lift the grippers and pull the upper. The machine comprises 20 mechanism which includes springs X³¹⁶, one of which is shown in Fig. 3, for moving the grippers inwardly over the shoe to over-draw the upper into position to receive the fastening tacks; and also comprises mechanism 25 for moving the grippers outwardly against the tension of the springs X³¹⁶ into position to grip the upper. The mechanism for moving the grippers outwardly also acts for holding said grippers in such outward 30 position during the up-draw movement imparted by the levers 154^x, 154^x, and e' for pulling and stretching the upper. This mechanism for moving the grippers outwardly comprises a connection—not shown—35 between the cam 804^x and the shaft 812^x, which shaft is provided with a pinion 822^x engaging rack-teeth 820^x on the slide 818^x. The slide 818^x actuates a slide 638^x which is provided with a depending lug 840^x in engagement with a stud 326^x on a second slide 322^x having an arm for engaging the shanks 68^x of the toe grippers and a connection—not shown—with the side grippers. These mechanisms may be the same as the mechanisms 40 for these purposes shown and described in Letters Patent No. 663,777 before mentioned.

The operation of pulling-over a shoe as carried out by this machine is briefly stated as follows: The shoe is presented by the 50 workman bottom upward to the machine, with the inner-sole against the sole-rest and with the outwardly and upwardly extending edges of the upper and lining materials between the open jaws of the grippers. The 55 grippers are first closed to grip the upper and then raised to pull it about the last, the last being held from upward movement by the sole-rest. Preferably the toe grippers are put into action first to pull and thereby 60 straighten the upper longitudinally over the face of the last, and then the side grippers are brought into action to pull the sides of the upper and shape the upper to the last along the ball and instep parts of the last. 65 Simultaneously with the action of the grippers

in pulling the upper, the heel-rest is moved forward into supporting engagement with the heel end of the last. The grippers actuating mechanism and the heel-rest actuating mechanism are so timed that the grippers will first have pulled the upper enough to have pressed the shoe firmly against the sole-rest by the time the heel-rest comes into supporting engagement with the heel of the last. While the side grippers are still moving, the sole-rest carrier is rocked about its pivot by the cam 140 to depress the toe portion of the last against the tightly strained upper for sinking the last downwardly into the upper and causing the upper to conform to the shape of the last. The sole-rest and the heel-rest in the normal adjustment of the machine are moved forwardly during the latter part of the pulling movement of the grippers, the sole-rest, it may be, acting to 75 force the inner-sole forwardly on the last to bring its toe end flush with the toe end of the last and in contact with the upstretched toe portion of the upper, and the heel-rest acting to carry the last forwardly with relation to the upper as the latter is held by the grippers and thereby cause the upper to be strained backwardly over the last, particularly along the ball portion of the last while it is pulled taut by the side grippers, where- 80 by this portion of the upper is made to conform to the lines of the last over the ball. These operations having taken place the machine is brought to rest to permit the operator to examine the shoe and, if necessary, 85 manually to shift the heel-rest or the sole-rest, or both of them, by means of the hand lever 160 to adjust the last and to position the inner-sole, if, upon inspection, he finds that these operations have not been com- 90 pletely and satisfactorily performed for the particular shoe in hand by the automatic operation of the machine as just described. When the machine is re-started, the arms carrying the last-supporting and wiping and 95 pressing mechanisms are moved into position against the sides of the last by the action of the cam N³³ on the slide N²⁶, and as the last-supports and wipers and pressers come into engagement with the upper on the sides 100 of the last, the grippers are moved inwardly over the last to over-draw the upper and then they release the upper. The grippers are followed closely in their movement over the inner-sole of the shoe by the tack-carrying 105 blocks and the drivers by which the tacks are inserted at the toe and at the sides to secure the pulled-over upper to the inner-sole. 110

Having thus described my invention, I 115 claim as new and desire to secure by Letters Patent of the United States:—

1. In a machine of the class described, means for pulling an upper over a last, a heel-rest and a sole-rest, and mechanisms 120

for automatically actuating said rests, in combination with a manually operated part normally connected with both the heel-rest and the sole-rest for moving them independently of said actuating mechanism.

5 2. In a pulling-over machine, means for pulling an upper over a last, a rest for the heel of the last, a rest for the sole of the last, and actuating mechanisms for said 10 rests, each of said actuating mechanisms comprising a ratchet and a pawl movable automatically into and out of engagement with its ratchet, and means for controlling the operation of the pawls to vary the 15 amount of movement imparted to the heel-rest and the sole-rest.

3. In a pulling-over machine, means for pulling an upper over a last, a rest for the last, and mechanism for actuating said rest, 20 said actuating mechanism comprising two shafts normally connected and adapted to be disconnected for discontinuing the movement of the rest.

4. In a pulling-over machine, means for 25 pulling an upper over a last, a rest for the last, and mechanism for actuating the rest, said actuating mechanism comprising a cam, a shaft operatively connected therewith, a second shaft and means for adjustably connecting said two shafts whereby the position 30 of the rest may be adjusted.

5. In a pulling-over machine, means for pulling an upper over a last, a rest for the last, automatic actuating mechanism for said 35 rest, a manually operated lever normally connected with said actuating mechanism, and means under the control of the workman for disconnecting said lever from said actuating mechanism.

40 6. In a pulling-over machine, means for pulling an upper over a last, a heel-rest and a sole-rest, in combination with mechanisms for actuating said rests, a hand lever normally connected with both of said mechanisms, and manually controlled means for disconnecting said lever from one of said mechanisms.

50 7. In a pulling-over machine, means for pulling an upper over a last, a rest and mechanism for actuating said rest to move the last, said mechanism including a stop to prevent reverse movement of the rest, and means under the control of the workman for rendering said stop inoperative whereby the 55 rest is permitted to retreat under pressure of the last against it.

8. In a pulling-over machine, means for pulling an upper over a last, a sole-rest, a heel-rest, and mechanisms for actuating said 60 rests, said mechanisms including stops to prevent reverse movement of the rests, and means under control of the workman adapted to render one or both of said stops inoperative.

65 9. In a pulling-over machine, means for

pulling an upper over a last, a heel-rest, a sole-rest, and actuating mechanisms for said rests, said actuating mechanisms comprising a plurality of pawls, a pawl-disengaging device adapted to act on said pawls successively, and a plurality of spring actuated stops arranged to be engaged successively by said disengaging device and to offer progressively increasing resistance to the movement of the disengaging device at different 70 positions thereof corresponding to the positions for disengaging the different pawls.

10. In a pulling-over machine, means for pulling an upper over a last, a sole-rest, automatic actuating mechanism for moving 80 the sole-rest, manually controlled means for additionally moving said sole-rest, and a stop to lock said sole-rest in the position to which it is manually moved.

11. In a pulling-over machine, means for pulling an upper over a last, a rest for the heel of the last, actuating mechanism for said rest, a manually operated lever normally connected with said actuating mechanism, and means for disconnecting said manually operated lever from the heel-rest actuating mechanism.

12. In a pulling-over machine, a heel-rest, automatic mechanism for advancing said heel-rest, a sole-rest, automatic mechanism for advancing said sole-rest, stops for preventing return movement of said rests, a manually controlled part normally connected with said sole-rest and said heel-rest and adapted to be operated for giving said rests 100 additional forward movements, and a device arranged to be operated at the will of the workman for disconnecting the manually controlled part from the heel-rest and simultaneously rendering said sole-rest stop inoperative, whereby the sole-rest may be moved backwardly as well as forwardly by the manually controlled part.

13. In a pulling-over machine, a heel-rest, automatic mechanism for advancing said heel-rest, a sole-rest, automatic mechanism for advancing said sole-rest, stops for preventing return movement of said rests, a manually controlled part normally connected with said sole-rest and said heel-rest and adapted to be operated for giving said rests additional forward movements, and a device arranged to be operated at the will of the workman for disconnecting the manually controlled part from the heel-rest and simultaneously rendering said sole-rest stop inoperative, whereby the sole-rest may be moved backwardly as well as forwardly by the manually controlled part, said device being 115

adapted to be operated for rendering the said heel-rest stop inoperative whereby the heel-rest is permitted to move backwardly.

14. In a pulling-over machine, the combination with means for pulling an upper over 120

5 a last, a heel-rest, a sole-rest, and a manually controlled part normally connected with said sole-rest and heel-rest and adapted to be operated for giving said rests forward movements, of stops to prevent reverse movements of said rests, and a device arranged to be operated at the will of the workman for disconnecting the manually controlled part from the heel-rest and rendering said sole-
10 rest stop inoperative, whereby the sole-rest may be moved backwardly as well as forwardly by the manually controlled part.

15 15. In a pulling-over machine, the combination with means for pulling an upper over a last, a sole-rest, and a rest for the heel of the last, of manually controlled means for moving the sole-rest and heel-rest, said manually controlled means being normally connected with said rests and adapted to be disconnected from the heel-rest, whereby the sole-rest may be moved alone.

20 16. In a pulling-over machine, the combination with means for pulling an upper over a last, a sole-rest, and a rest for the heel of the last, of manually operated means for actuating the sole-rest and heel-rest, a pawl carried by said manually operated means, and means under the control of the workman for disconnecting said pawl from the heel-rest actuating mechanism.

25 17. In a pulling-over machine, the combination with a heel-rest, actuating mechanism therefor, a sole-rest, and mechanism arranged for automatically moving the sole-rest in the regular operation of the machine, of a part arranged for manual operation to move the sole-rest independently of the regular operation of the machine, and a device for disconnecting the sole-rest from its 30 automatic actuating mechanism to permit its independent operation by said manually operated part, said device being also constructed and arranged to disconnect the heel-rest from its actuating mechanism, whereby the heel-rest is permitted to move backwardly.

35 18. In a pulling-over machine, the combination of a sole-rest, a heel-rest, and means normally connected to the sole-rest and heel-rest and arranged to be operated by the workman to move said rests together, of means for disconnecting the heel-rest therefrom so that the sole-rest may be moved alone.

40 19. In a pulling-over machine, a sole-rest, a heel-rest, and automatic means for actuating said rests, said means comprising a cam, a block, a connection between the cam and the block, a plunger, connections between the block and plunger for actuating the latter, pawls carried by said plunger, and ratchets arranged to be actuated by said pawls, and having operative connections with the heel-rest and sole-rest.

45 20. In a pulling-over machine, a sole-rest,

a heel-rest, and automatic means for actuating said rests, said means comprising a cam, a block, a connection between the cam and the block, a plunger, connections between the block and plunger for actuating the latter, pawls carried by said plunger, and ratchets arranged to be actuated by said pawls and having operative connections with the heel-rest and sole-rest, combined with relatively adjustable controlling devices for disengaging the pawls from their ratchets during the upstroke of the plunger and permitting the pawls to engage their ratchets during different portions of the downstroke of the plunger for producing the desired movements of said two rests.

50 21. A machine of the class described having, in combination, means for working an upper over a last, a rest for the heel end face of the last, a sole-rest, and a manually operated device normally connected with both the heel-rest and the sole-rest for actuating them to move said rests relatively to the overworking means.

55 22. A machine of the class described having, in combination, a heel-rest, a sole-rest, and a manually operated part normally connected with both the heel-rest and the sole-rest, said machine having provision for permitting said manually operated part to be disconnected from one of said rests at the will of the operator to permit further movement of the other rest alone.

60 23. A machine of the class described having, in combination, a heel-rest, a sole-rest, and a manually operated part normally connected with both the heel-rest and the sole-rest, said machine having provision for permitting one of said rests to be moved by said part farther than the other rest at the will of the operator.

65 24. A machine of the class described having, in combination, a heel-rest, a sole-rest, and a manually operated part normally connected with both the heel-rest and the sole-rest, said machine having provision for locking one rest after it has been moved and permitting further movement of the other rest by said manually operated part.

70 25. A machine of the class described having, in combination, a heel-rest, a sole-rest, and a manually operated part connected with both the rests for moving them and adapted at the will of the operator to move one rest farther than the other, combined with means for returning the rests always to the same initial position irrespective of the distances through which they may have been moved.

75 26. A machine of the class described having, in combination, means for pulling an upper over a last, a heel-rest, a sole-rest, automatically actuated mechanism for actuating said rests, and a lever normally connected with both of said rests for actuating them

manually, said lever being adapted to be disconnected from one of said rests to permit manual actuation of the other.

27. A pulling-over machine having, in combination, two manually operated members, and actuating mechanisms therefor comprising a hand lever, pawls connecting the lever with said mechanisms, a single pawl disengaging device arranged to act upon said pawls successively, and means arranged to become operative after the device has disengaged one of the pawls to warn the workman that further movement will disengage another pawl.
28. A pulling-over machine having, in combination, two manually operated members, and actuating mechanisms therefor comprising a hand lever, pawls connecting the lever with said mechanisms, a single pawl disengaging device arranged to act upon said pawls successively, and a plurality of springs arranged to become operative successively to warn the operator by the change in resistance when the successive pawls are about to be acted upon by the disengaging device.
29. A machine of the class described having, in combination, two members, and

mechanism for actuating them comprising a single manually operated lever, a locking device to hold said lever in its adjusted position, a second device for connecting the lever with one of said members, a device adapted first to disengage the locking device and then said connecting device, and means arranged to become operative during the movement of the disengaging device to enable the operator to detect when further movement will actuate said connecting device.

30. In a machine of the class described, shoe resting means, means for advancing said means, locking means therefor including coöperating ratchet teeth and two pawls, a lost-motion connection between the two pawls, and means connected with one pawl and operating indirectly through said connection upon the other pawl to release said pawls from the ratchet teeth.

In testimony whereof I have signed my name to this specification in the presence of two subscribing witnesses.

RONALD F. McFEELY.
